UNITED STATES PATENT OFFICE.

HERMAN C. PRIEBE, OF BLUE ISLAND, ILLINOIS.

DRAFT GEAR.

Application filed May 23, 1921. Serial No. 471,702.

To all whom it may concern:

Be it known that I, HERMAN C. PRIEBE, citizen of the United States, residing at Blue Island, in the county of Cook and State 5 of Illinois, have invented a certain new and useful Improvement in Draft Gears, of which the following is a full, clear, concise, and exact description.

My invention relates to draft gears that 10 employ springs for resisting pushing and pulling draft strains.

The invention has for one object the employment of a spring of flattened formation which is adapted, by its shape, for location 15 between the sides of coupler yokes without impairing its capacity.

The invention also has for its object the provision of a plurality of springs between the sides of a coupler yoke that engage fol- 20 lower plates at the ends of the yoke.

As the invention is practiced the coupler yoke is disposed between longitudinal sills which may be the center sills of the car. Keys are passed through these sills and the 25 yoke, there being springs upon the outer sides of the sills and interposed between the keys to oppose the approach of either key toward the other. The follower plates pass through the yoke and terminate at the inner 30 faces of the sills, one follower plate being engageable by one end of the yoke and the other follower plate by the other end of the yoke. Two springs pass through the yoke and are interposed between and en- 35 gage said follower plates, these springs having bores that are oblong in cross section and being formed of helically wound ribbons, the aforesaid keys passing between the springs whereby the greatest spring capac- 40 ity within the available space is afforded. There are other springs upon the outer sides of the sills that are interposed between the keys whereby the proper relationship of the keys with each other and with the bal- 45 ance of the draft gear is maintained.

There is thus provided a draft gear, in the preferred embodiment of the invention, in which spring mechanism is interposed between the keys and in which spring mechanism is interposed between follower plates that are acted upon by the keys and while the keys preferably pass through the sills where the spring mechanism associated therewith is upon the exterior of the sills 55 and while the spring mechanism that is surrounded by the coupler yoke is preferably formed as described, I do not wish to be limited to all these characteristics in all embodiments of the invention.

I will explain my invention more fully 60 by reference to the accompanying drawings, in which Fig. 1 is a view in plan, partially in section, of a draft gear constructed in accordance with the preferred embodiment of the invention; Fig. 2 is a side view of the 65 structure shown in Fig. 1 minus the coupler shank; Fig. 3 is a sectional view on line 3-3 of Fig. 1 minus the coupler shank; Figs. 4 and 5 are sectional views taken respectively upon lines 4-4 and 5-5 of Fig. 70 1; Fig. 6 is a cross sectional view of a modification; and Fig. 7 is a side elevation of the modification shown in Fig. 6.

Like parts are indicated by similar characters of reference throughout the different 75 figures.

The draft gear shown includes any usual or suitable coupler of which a shank 1 is illustrated, this coupler shank being assembled by means of a key 2 with the coupler 80 yoke 3. This coupler shank, however, may be otherwise assembled with the coupler yoke. The coupler yoke illustrated has an elongated space between its sides 4 and 5 that are arranged one above the other. 85 Key 6 and 7 are passed through slots 8 in the center sills 9, these keys being embraced by the coupler yoke through the space of which they pass. Stirrups 10 embrace the 90 keys, the inner opposing faces of these stirrups being engaged by the springs 11 that are upon the outer sides of the center sills, these springs exerting spreading action thereupon with a tendency to maintain the 95 keys in engagement with the aforesaid ends of the yoke as illustrated. Follower plates 12, 13 also pass through the coupler yoke, these follower plates being disposed altogether between the sides of the center sills, the follower plate 12 being limited in its 100 outward movement by the cheek plates 14 and the follower plate 13 being limited in its inward movement by the cheek plates 15. Two more springs 16 and 17 with their axes disposed longitudinally of the center sills, 105 pass through the yoke and are interposed between and engage the follower plates to have action thereupon independently of the springs 11. In order that these springs may be disposed within the comparatively 110 narrow space of the yoke they are formed of helically wound ribbons and flattened.

A member 18, substantially of the thickness of the keys 6 and 7, is interposed between the springs 16 and 17 to maintain them apart and is of such width, measured lengthwise of the gear, as to engage both keys 6 and 7 when the springs have been compressed to the limit intended. The member 18 floats so that either key may move it toward the other.

10. In the embodiment of the invention illustrated in Figs. 6 and 7 nested co-axial springs 19, 20 and 21 are disposed between the sides of the coupler yoke, these springs being flattened and formed of helically wound ribbons, the axes of the springs extending lengthwise of the gear. These springs engage the follower plates 12 and 13. The springs shown in Figs. 6 and 7, similarly to the springs 16 and 17, are of 20 maximum capacity because of their flattened formation and the construction thereof of helically wound ribbons.

While I have herein shown and particularly described the preferred embodiment 25 of my invention I do not wish to be limited to the precise details of construction shown as changes may readily be made without departing from the spirit of my invention, but having thus described my invention I claim 30 as new and desire to secure by Letters Patent the following:—

1. A draft gear including a coupler yoke; longitudinal sills between which said yoke is disposed; keys passing through said sills and said yoke; springs upon the outer sides of said sills and interposed between said keys to oppose the approach of either key toward the other; follower plates passing through the yoke, one follower plate being 35 engageable by one end of the yoke and the other follower plate by the other end of the yoke; two springs also passing through the yoke and interposed between and engaging said follower plates, these springs being flattened, the aforesaid keys passing between the springs; and a floating motion limiting member interposed between said keys.

2. A draft gear including a coupler yoke; longitudinal sills between which said yoke is disposed; keys passing through said sills and said yoke; springs upon the outer sides of said sills and interposed between said keys to oppose the approach of either key toward the other; follower plates passing 55 through the yoke, one follower plate being engageable by one end of the yoke and the other follower plate by the other end of the yoke; and two springs also passing through the yoke and interposed between and engaging said follower plates, these springs being flattened, the aforesaid keys passing between the springs.

3. A draft gear including a coupler yoke; longitudinal sills between which said yoke 60 is disposed; keys passing through said sills

and said yoke; springs upon the outer sides of said sills and interposed between said keys to oppose the approach of either key toward the other; follower plates passing through the yoke, one follower plate being engageable by one end of the yoke and the other follower plate by the other end of the yoke; two springs also passing through the yoke and interposed between and engaging said follower plates, the aforesaid keys passing 70 between these springs; and a floating motion limiting member interposed between said keys.

4. A draft gear including a coupler yoke; longitudinal sills between which said yoke is disposed; keys passing through said sills and said yoke; springs upon the outer sides of said sills and interposed between said keys to oppose the approach of either key toward the other; follower plates passing 80 through the yoke, one follower plate being engageable by one end of the yoke and the other follower plate by the other end of the yoke; and two springs also passing through the yoke and interposed between and engaging said follower plates, the aforesaid keys passing 85 between the springs.

5. A draft gear including a coupler yoke; longitudinal sills between which said yoke is disposed; keys passing through said yoke and sills; follower plates passing through the yoke, one follower plate being engageable by one end of the yoke and the other follower plate by the other end of the yoke; and two springs also passing through the yoke and interposed between and engaging said follower plates, these springs being flattened, the aforesaid keys passing 95 between the springs.

6. A draft gear including a coupler yoke; longitudinal sills between which said yoke is disposed; keys passing through said yoke and sills; follower plates passing through the yoke, one follower plate being engageable by one end of the yoke and the other follower plate by the other end of the yoke; two springs also passing through the yoke and interposed between and engaging said follower plates, these springs being flattened, the aforesaid keys passing 105 between the springs; and a floating motion limiting member interposed between said keys.

7. A draft gear including a coupler yoke; longitudinal sills between which said yoke is disposed; keys passing through said yoke and sills; follower plates passing through the yoke, one follower plate being engageable by one end of the yoke and the other follower plate by the other end of the yoke; two springs also passing through the yoke and interposed between and engaging said follower plates, the aforesaid keys passing 110 between the springs; and a floating motion limiting member interposed between said keys.

120

130

8. A draft gear including a coupler yoke; longitudinal sills between which said yoke is disposed; keys passing through said yoke and sills; follower plates passing through the yoke, one follower plate being engageable by one end of the yoke and the other follower plate by the other end of the yoke; and two spring also passing through the yoke and interposed between and engaging said follower plates, the aforesaid keys passing between the springs. ¹⁰

In witness whereof I hereunto subscribe my name this 18th day of May, A. D. 1921.

HERMAN C. PRIEBE.
